S. S. JACKSON.
COMPENSATING HEAD GEAR FOR LOOMS.
APPLICATION FILED JULY 20, 1909.

986,634.

Patented Mar. 14, 1911.

UNITED STATES PATENT OFFICE.

SIMEON SCHOON JACKSON, OF READVILLE, MASSACHUSETTS.

COMPENSATING HEAD-GEAR FOR LOOMS.

986,634.

Specification of Letters Patent. Patented Mar. 14, 1911.

Application filed July 20, 1909. Serial No. 508,610.

To all whom it may concern:

Be it known that I, SIMEON SCHOON JACKSON, a subject of Great Britain, residing at Readville, in the county of Norfolk, State 5 of Massachusetts, have invented a certain new and useful Improvement in Compensating Head-Gear for Looms, of which the following is a specification, reference being had therein to the accompanying drawings.

10 The invention has relation to the class of devices which variously are termed compensating head-gears, roll-tops, over and under motions, or top-rigging, they consisting in general, of arrangements of levers, sheaves, 15 rolls, or other rockers, with which the respective harness-frames employed in a loom are connected, and being used in lieu of springs to act in conjunction with shedding tappets or cams in the production of the 20 successive sheds in the warp-threads.

The invention consists in novel and improved devices of the said class, especially contrived for employment in effecting those kinds of weaving necessitating the formation 25 of sheds in which a greater number of harness-frames is at one shed-level than at the other, alternately with sheds in which the relative numbers of harness-frames at the different shed-levels are reversed. Thus, 30 sometimes, the harness-frames are related in groups, and an entire group is required to occupy for certain shed-formations a position at either the upper level or the lower level, while another group is divided be- 35 tween the two levels, and for other shed-formations the first group is required to be divided between the two levels and the entire second group is required to occupy one or the other thereof. This, for instance, is the 40 case on weaving two-ply fabric in a loom having a single shuttle which is made to pass alternately through a shed in the upper ply and through a shed in the lower ply, as for instance in weaving tubular fabric 45 wherein the two plies are united along their edges, and also in weaving fabric having the two plies united along the other edge thereof.

One special object of the invention is to provide means for avoiding strain and break- 50 age in case the shedding tappet or cams, the devices for transmitting motion therefrom to the harness-frames, the strapping, or the head-gear itself should not be proportioned just right, and in case the timing of the dif- 55 ferent tappets or cams should not be perfect; so as thereby to render unnecessary an

extremely exact setting and adjustment of the parts, including the tappets or cams, and obviate injury and trouble in case of accident or disarrangement of the working 60 parts.

The invention is embodied in a movable carrier, a primary rocker in connection therewith, secondary rockers in opposed connection with the said primary rocker, each 65 of the said secondary rockers having a group of harness-frames in opposed connection therewith, an actuating cam for the movable carrier producing taking-up motion by which an entire group of harness-frames is 70 brought to the required level, and a give-away motion permitting an entire group to occupy the opposite level, and a give-and-take spring which renders the compensating 75 action yielding.

The invention is shown embodied for use in weaving tubular fabric comprising an upper ply and a lower ply, with the two plies united to each other at both edges of the 80 web in the loom.

Figure 1 of the drawings shows in front elevation the harness-frames, shedding-tappets or cams, etc., employed for weaving the tubular fabric referred to, and a head-gear embodying the invention. Fig. 2 is a side 85 view thereof.

Four harness-frames are shown, respectively marked 1, 2, 3 and 4. The treadles which are connected in usual manner with the said harness-frames are marked, respectively, 1^a, 2^a, 3^a, and 4^a, and the shedding-tappets or cams are marked respectively 1^b, 2^b, 3^b, 4^b. The said tappets or cams are of the shapes and relative arrangement usually employed for tubular weaving. They are 95 fixed upon jackshaft 5, the latter being driven from the crank-shaft 6 of the loom by spur-gears 5^a, 6^a, at the rate of one rotation of the jackshaft for two rotations of the cam-shaft. Strapping 7, 7^a, 7^b, 7^c, ex- 100 tends upward from the top bars of the harness-frames, and passes partly around the supporting sheaves 8, 8, to the head-gear.

The movable carrier of the head-gear is marked 9, the primary rocker which is piv- 105 oted thereon is marked 10, and 11, 11^a, are the secondary rockers which are pivoted upon the primary rocker. The said movable carrier is shown in the form of a bell-crank, which is hung upon the pivot 12 upon the 110 arch 13 of the loom-frame. The primary rocker is lever-shaped. The secondary car-

riers are each formed as a sheave of two different diameters, as customary.

The harness-frames 1 and 2 are utilized for controlling the warp-threads of one ply 5 of the fabric, and constitute one group. The strapping 7 of harness-frame 1 is wound partly around the portion of smaller diameter of secondary rocker 11, and made fast thereto, while the strapping 7^a of harness-frame 2 is wound in the opposite direction 10 partly around the portion of larger diameter of the said secondary rocker 11, and made fast thereto. Thus, the two harness-frames 1 and 2 are in opposed connection with the 15 said rocker 11, so that if either of the said harness-frames 1 and 2 is depressed by the action of its tappet or cam while the other thereof is left free to assume an elevated position, the unwinding of the strapping 20 connected with the frame that is depressed turns the rocker part way so as to wind upon it the strapping of the other frame, thereby raising the latter. The harness-frames 3 and 4 are utilized for controlling the warp-threads of the other ply of the fabric, and 25 constitute a second group.

The strapping 7^b of harness-frame 3 is wound partly around the portion of smaller diameter of secondary rocker 11^a, and made 30 fast thereto, and that, 7^c, of harness-frame 4 is wound in the opposite direction partly around the portion of larger diameter of said rocker 11^a, and made fast thereto. Thus the two harness-frames 3 and 4 are in 35 opposed connection with the said rocker 11^a, so as to cause them to act in the manner already explained in treating of harness-frames 1 and 2, in case either 3 or 4 is depressed while the other thereof is free to assume 40 an elevated position.

The secondary rockers 11 and 11^a, respectively are pivoted upon the primary rocker 10 at opposite sides of the pivot by which rocker 10 is mounted upon the carrier 9. 45 Consequently, the said secondary rockers are in opposed connection with the primary rocker. As a result, pull transmitted through the strapping of either group of the harness-frames, as the respective frames of 50 such group are depressed by the action of the shedding tappets or cams, will act to tilt the primary rocker upon its pivot in the direction to take up slack in the strapping of the harness-frames of the other group.

55 Thereby a balancing action is secured.

The shedding tappets or cams shown in the drawings are arranged to operate the harness-frames in the following order:—No. 2 down and Nos. 1, 3 and 4 up, as in the 60 drawings; 1, 2, and 3 down and 4 up; 1 down and 2, 3, and 4 up; 1, 2 and 4 down and 3 up. In the case of shed-formations 1 and 3, the depression of one of the harness-frames of the first group is insufficient to 65 take up the slack of the strapping sufficiently

to raise the other frame of such group and both frames of the second group completely to the required upper level. Consequently a supplemental taking-up action is required for the purpose of pulling up the strapping 70 and thereby further raising the said harness-frames until their treads 1^a, 3^a, and 4^a have taken firm bearing against their actuating tappets or cams 1^b, 3^b, 4^b. In the case of 75 shed-formations 2 and 4 the simultaneous depression of both harness-frames of the first group and one of the harness-frames of the second group calls for more letting-down of the strapping than is permitted by the rise of one harness-frame of the second group. 80 Consequently, a give-away action is required for the purpose of supplying an amount of slack sufficient to permit the depression of three harness-frames to the lower level. To 85 secure these taking-up and give-away actions, an actuating cam is provided, having connections between the same and the movable carrier through which it transmits to the latter at the proper times movements by which the rockers are shifted bodily in one 90 direction to effect the said supplemental taking-up and in the reverse direction to effect the giving-away. Thus, at 14 is a swiveling block which is hung by the pivot-pin 15 upon one arm of the carrier 9, and 16 is a rod 95 passing through holes in said block, said rod having a collar 17 fastened thereon below the block and being surrounded above the block by an expanding cushioning spring 18 that is confined between the block and adjustable nuts 19 which are applied to the threaded top portion of the rod. The lower end of the rod is connected with a treadle 20 which is engaged by a cam 21 fixed upon the cam-shaft 6. When the cam presses 100 against the said treadle, the required taking-up action is produced. When the said pressure is relieved, the give-away action is permitted to occur.

The cushioning spring 18 is of very great 110 practical importance. It yields to avoid strain and breakage in case the parts should not be proportioned just right, and in case the timing of the shedding tappets or cams and cam 21 should not be perfect. It 115 renders an extremely exact setting and adjustment of the parts unnecessary, and obviates injury and trouble in case of accident or disarrangement of the working parts.

What is claimed as the invention is:—

1. In a compensating head-gear for looms, the combination with harness-frames, and shed-forming tappets or cams actuating said harness-frames, of a movable carrier, a primary rocker in connection with said carrier and supported thereby, secondary rockers in opposed direct connection with said primary rocker, each secondary rocker having a group of harness-frames in opposed connection therewith, an actuating cam for the 120

125

130

movable carrier producing taking-up, and a give-and-take spring which renders the compensating action yielding.

2. In a compensating head-gear for looms, 5 the combination with harness-frames, and shed-forming tappets or cams actuating said harness-frames, of a movable carrier, a primary rocker in connection with said carrier, secondary rockers in opposed connection 10 with the said primary rocker, each secondary rocker having a group of harness-frames in opposed connection therewith, an actuating cam, and motion-transmitting devices between such cam and the carrier comprising 15 a rod, a swivel hung to the carrier and through which the rod passes, and a cushioning spring in connection with the rod acting against the swivel.
3. In a compensating head-gear for looms,

the combination with harness-frames, and 20 shed-forming tappets or cams actuating said harness-frames, of a movable carrier, a primary rocker in connection with said carrier, secondary rockers in opposed connection 25 with the said primary rocker, each having a group of harness-frames in opposed connection therewith, an actuating cam, a lever actuated by the said cam, a rod connected with the said lever, and a swivel hung to the 30 said carrier and through which the rod transmits motion to the carrier.

In testimony whereof I affix my signature in presence of two witnesses.

SIMEON SCHOON JACKSON.
